DISPENSING CARTON FOR WRAPPING MATERIAL IN THE FORM OF SHEETS AND FILMS

Robert H. Durdan, Buffalo, N.Y.

Application January 11, 1957, Serial No. 633,710

4 Claims. (Cl. 225—48)

This invention relates generally to the class of receptacles and is directed particularly to improvements in those receptacles or boxes designed for marketing and also for dispensing rolled sheet material.

The use of various types of sheet material for wrapping articles, particularly in the home for wrapping foodstuffs or the like for the purpose of preserving the same, is very extensive. Such sheet materials are in the form of aluminum foil, waxed paper or transparent plastic film of a special design which is treated with static electricity so that it will readily adhere to itself or to objects about which it is wrapped. Such materials are generally marketed in rolls which are enclosed in boxes or cartons from which the material may be withdrawn in the desired length and means is usually provided upon the box or carton for facilitating the tearing off of the withdrawn length of the sheet or film.

In the case of the above referred to specially designed plastic film, it has been the experience of many persons using the same that after a portion of the film has been torn from the roll, the free end will slip back into the box and strongly attach itself to the adjacent surface of the roll, with the result that when another section of the film is desired for use, great difficulty is experienced not only in finding the edge of the material but in grasping it and getting it started from the roll to be withdrawn from the carton.

In view of the foregoing, it is a particular object of the present invention to provide a new and novel box or receptacle which is designed particularly, although not necessarily exclusively, for merchandising rolls of the above referred to special film and more especially for facilitating the easy withdrawal of a portion of the film and its removal for use and for retaining the free end of the roll in a position where it can again be easily grasped when another section is desired for use.

Another object of the invention is to provide a box or receptacle for the above described purpose which is so constructed or designed that the film or sheet of material as it is being withdrawn will run over a smooth edge and between spaced portions of a wall of the receptacle where the free end will be held or retained after the desired withdrawn portion has been detached from the roll.

Still another object of the invention is to provide an improved box or carton for the purpose stated wherein there is provided a portion of one wall in the form of a panel beneath which the free end of the roll will be retained and which, in the event that such free end of the roll should for any reason slip back into the carton, can be raised to give access to the roll and then be replaced to provide a guide and covering means for the end portion.

A still further object of the invention is to provide a novel form of blank in one piece which is adapted to be folded to form the box or carton and to provide a top portion in two overlapping parts or panels which cooperate to form a guide for the sheet or film material

2

as it is drawn from the carton and to retain the free end of the material after the sheet has been cut off.

A still further object of the invention is to provide in a box or receptacle of the character stated, a new and novel type of cutter which functions with greater efficiency than cutters of the type at present in use, thereby insuring the clean cutting of the sheet without crumpling and which will not become ineffective by reason of clogging by portions of the film or sheet adhering thereto.

The invention will be best understood from a consideration of the following detail description taken in connection with the accompanying drawings forming part of the specification, with the understanding, however, that the invention is not confined to a strict conformity with the showing of the drawing but may be changed or modified so long as such changes or modifications mark no material departure from the salient features of the invention as expressed in the appended claims.

In the drawings:

Fig. 1 is a view in perspective of a box or carton constructed in accordance with the present invention, the same being shown with the movable top panel closed down or secured and showing this top panel in broken or dotted outline in raised position;

Fig. 2 is a view in perspective of one end of the carton showing the same in partially folded condition and illustrating the relation which the different attaching tabs and end wall panels assume in the folding of the box;

Fig. 3 is a transverse section taken substantially on the line 3—3 of Fig. 1, illustrating an end portion of a film roll between the fixed and movable top wall panels;

Fig. 4 is a view in perspective illustrating the manner of severing the withdrawn film against the cutting teeth at the bottom of the front wall of the carton;

Fig. 5 is a plan view of the carton blank; and

Fig. 6 is a plan view of the cutter strip per se, with the central portion thereof broken away.

Referring now more particularly to the drawings, the numeral 10 generally designates the complete closed box or carton of the present invention. This box or carton, except for the hereinafter described cutting strip, is formed from a single blank of material such as cardboard or the like, as shown in Fig. 5 where the blank is generally designated B. The blank as shown in Fig. 5, is of generally rectangular form and for housing a roll of sheet material is, of course, of materially greater length than width, the numerals 12 and 14 designating the longitudinal edges while the overall length of the completed box is designated by the transverse dot and dash lines 16. These lines 16 also represent the fold lines for the end walls and attaching tabs as hereinafter described.

The blank is laid off longitudinally to define a number of panels each of which in the completed carton will form a wall or a portion of a wall. These panels are designated 18, 20, 22, 24 and 26, being separated by the fold lines 27, 28, 29 and 30.

The panel 20 in the completed box or carton forms the fold wall which, in the other figures, is designated 20' while the panel 22 forms the bottom wall of the carton designated 22' and the panel 24 forms the back wall of the carton designated 24'. The panels 18 and 26 overlap and cooperate in the completed carton to form the top wall which is generally designated 31.

The front wall forming panel 20 is provided at each end with a tab 32 the width of which, which in the blank is directed lengthwise of the panel, is approximately half the width of the hereinafter described end wall of the carton, and the end edges are cut along outwardly convergent lines as indicated at 33 and 34 to facilitate folding.

At each end of the bottom wall forming panel 22 is the end wall panel 35 which, in the completely formed

box, forms the end wall 35' as illustrated in Figs. 1, 2 and 4.

The outer edge of each panel 35, by which is meant the edge of the panel farthest from the panel 22 from which it extends, is cut across the major portion of the width of the panel to form the oblique or inclined edge 36 which at its innermost end joins an inner edge 37 of an ear 38.

The numeral 39 designates an attaching tab at each end of the back wall forming panel 24. These tabs are of the same width as the tabs 32 and the side edge of each nearest to a panel 35 extends obliquely across the width of the tab in divergent relation with the adjacent edge of the panel 35, as indicated at 40. The opposite side edge of each panel 39 from the edge 40 is notched as at 41 to match the form of the outer edge of the adjacent end wall panel 35 when the box is folded.

Each end of the panel 18 has extending therefrom or joined thereto a narrow securing tongue 42.

The panel 26 which forms a part of the top wall 31 in association with the panel 18 is folded lengthwise along the line 43 which fold line is relatively close to the fold line 30 so that the panel is divided into two parts *a* and *b*.

In folding the blank B to form the box or carton the panels 20 and 24 are folded up along the lines 28 and 29 so as to be disposed vertically at right angles to the panel 22, thus forming the hereinbefore referred to front and back walls 20' and 24' respectively and the outlying panels 18 and 26 are likewise folded along the fold lines 27 and 30. In folding these panels 18 and 26 they would be folded inwardly toward the inner faces of the adjacent panels 20 and 24, respectively, but the panel 26, when folded along the line 43, would be bent so that the part *b* would be turned back against the outer face of the smaller part *a*. The end wall panels 35, the tabs 32 and 39 and the tongues 42 are all bent or folded inwardly along the lines 16.

Tabs 32 and 39 at the two ends of the panel are glued to the inner faces of the adjacent end wall panels 35. Fig. 2 illustrates the manner in which the front and back walls at one end of the carton are placed in position against the inner surface of the adjacent panel 35 which when bent up forms the end wall 35'. After the tabs are secured in the manner stated to the end wall panels the roll of sheet material is placed within the carton and the panel 18 is then folded in until it rests at its ends upon the inclined edges 36 of the end wall forming panels. In making this fold the tongues 42 are positioned against and glued to the outer faces of the adjacent end wall panels.

It will be seen upon reference to the blank in Fig. 5 that the edge 33 of each tab 32 is so angled that when the tab is glued into position such edge will lie parallel with or slightly below the edge 36 of the adjacent end wall panel. Likewise the notch 41 formed in the side of each of the tabs 39 will conform to the inclined edge of the adjacent end wall panel 35 and the ear portion 38, as is clearly shown in Figs. 1 and 4.

The narrow strip portion *a* of panel 26 is folded down to extend at a downward and forward inclination between the ear portions 38 of the end walls and the conforming portions of the tabs 39 at the inner sides of the end walls and the wider part *b* of the panel 26 which may be defined as the flap, is brought down against the surface of the panel 18.

The numeral 44 generally designates a cutter which is secured along the outer face of the front wall 20' at the bottom edge thereof. This cutter comprises a strip of metal 45 or any other suitable material, which along one edge is formed to provide a row of cutting teeth 46. These teeth 46 are all relatively sharp pointed as shown, and are disposed to project outwardly from the body of the strip at an oblique angle to the length

thereof and as shown in Fig. 6, the teeth are all pointed in the same direction. The teeth are set so that when the strip is secured to the wall 20' by rivets 47 or in any other desired manner, they will point away from the person using the box or carton when holding the latter in the left hand with the wall 20' directed to the right. Since the majority of persons are right handed, the cutter is set to have the teeth pointing away from the user when the carton is held as described so that when the film or strip of material is drawn out as shown in Fig. 4 where the drawn-out part to be torn off is designated 48, and the free edge of the drawn-out portion is grasped with the right hand, it can be pulled down against the pointed teeth 46 and easily cut from the roll. The roll in Fig. 3 is generally designated 49 and in this figure the edge portion of the material is shown in between the part *b* of the panel 26 and the panel portion 18.

In tearing away a section of the roll of film in the manner shown in Fig. 4, it will be seen that a substantial portion of the film will be left and will remain outside of the carton, extending from the carton between the overlapping panels 18 and 26 which form the top wall 31 and thus the edge of the material may be easily grasped when it is next desired to withdraw a portion of the roll of material for use.

If for any reason the end of the material should get back into the box, the user may open the box by pulling up on the panel 26 and thus obtain access to the roll through the open area designated *c* in Fig. 3 which is provided between the longitudinal edge of the panel 18 and the back wall 24'. If the roll end cannot be reached in this manner, then the end tongues 42 may be detached so that the panel 18 can be swung to open position also and the roll may be removed from the box. When the roll is replaced, the panels 18 and 26 will be returned to the positions shown in Figs. 1, 3 and 4 and although the end tongues 42 and the panel 18 will not be secured, the pressure of the thumb of one hand against the panel 26 will keep the panel 18 from slipping out of position.

The panel 26 will also be retained in its operative position by reason of the fact that the portion *a* thereof lies between the upstanding ears 38 of the end wall panels and the adjacent portions of the tabs 39 which are secured against the inner faces of the end wall panels, such retention of the portion *a* being effected by its frictional engagement with the inner faces of the ends of the carton which the end wall panels and the tabs 39 provide.

The combination of the end wall panels 35 and the tabs 33 and 39 provide end structures for the carton of double thickness which will rigidify the carton so that it cannot become distorted in use.

From the foregoing, it will be apparent that there is provided by the present invention a new and novel box or carton structure particularly well adapted for merchandising rolls of material of the character described and especially well adapted for dispensing roll material of the particularly described plastic type which heretofore has presented certain difficulties in connection with its use in other types of cartons.

It will also be apparent that there is provided a type of cutter for attachment to a carton of the character stated which will more efficiently cut the withdrawn material by reason of the manner in which the teeth are formed and disposed along the edge of the carton.

I claim:

1. A one-piece carton for dispensing selected lengths of sheet material from a roll of such material contained in the carton, the carton comprising front, bottom, back and end walls, wherein each of the end walls is characterized by a panel joined to an end of the bottom wall and two attaching flaps secured against the inner face of the panel, one of the two flaps being joined to an end of the front wall and the other being joined to an end of the back

wall, each end wall panel having its top edge sloping downwardly and rearwardly from its front edge through a part of its length and terminating in an upstanding ear, a top wall first panel joined to the top of the front wall and having a width substantially equal to the length of the sloping edges of the end wall panels and lying on said edges, said top wall first panel having a downturned ear at each end secured to the outer side of the adjacent end wall panel, a top wall second panel pivotally secured to the top of the back wall along a fold line and having a portion lying between the upstanding ears of the end wall panels and a portion projecting widthwise upwardly and forwardly over the top wall first panel, said top wall panels coacting to provide a guide for a selected length of the sheet material drawn from the roll and a retaining means for a remaining end portion of the material, and a cutter secured along an edge of the front wall.

2. In a one-piece carton for dispensing selected lengths of sheet material from a roll of such material contained in the carton, the carton comprising front, bottom, back and end walls, wherein each of the end walls is characterized by a panel joined to an end of the bottom wall and two attaching flaps secured against the inner face of the panel, one of the two flaps being joined to an end of the front wall and the other being joined to an end of the back wall, each end wall panel having its top edge sloping downwardly and rearwardly from its front edge through a part of its length and terminating in an upstanding ear, a top wall first panel joined to the top of the front wall and having a width substantially equal to the length of the sloping edges of the end wall panels, said top wall first panel having a terminal ear at each end secured to the adjacent end wall panel, a top wall second panel pivotally secured to the top of the back wall and having a portion lying between said upstanding ears of the end wall panels and a portion projecting widthwise upwardly and forwardly over and adapted to rest upon the top wall first panel, said top wall panels coacting to provide a guide means for a selected length of the sheet material drawn from the roll and a retaining means for a remaining end portion of the material, and a cutter positioned along an edge of and carried by the front wall.

3. A one-piece carton for dispensing selected lengths of sheet material from a roll of such material contained in the carton, the carton comprising front, bottom, back and end walls, each of the end walls being characterized by a panel of predetermined width joined to an end of the bottom wall and two attaching flaps secured against the inner face of the panel, one of the two flaps being joined to an end of the front wall and the other of the

two flaps being joined to an end of the back wall, each of said flaps having a width no greater than one-half the width of said panel, each end wall panel having its top edge sloping downwardly and rearwardly from its front edge through a part of its length and terminating in an upstanding ear, a top wall first panel joined to the top of the front wall and having a width substantially equal to the length of the sloping edges of the end wall panels and lying on said edges, said top wall first panel having a downturned ear at each end secured to the outer side of the adjacent end wall panel, a top wall second panel pivotally secured to the top of the back wall along a fold line and having a portion lying between the upstanding ears of the end wall panels and a portion projecting widthwise upwardly and forwardly over the top wall first panel, said top wall panels coacting to provide a guide for a selected length of the sheet material drawn from the roll and a retaining means for a remaining end portion of the material, and a cutter secured along an edge of the front wall.

4. A one-piece carton for dispensing selected lengths of sheet material from a roll of such material contained in the carton, the carton comprising front, bottom, back and end walls, a panel joined to the top of the front wall and projecting rearwardly and downwardly, a panel pivotally joined to the top of the back wall along a fold line and extending forwardly in overlapping relation with the first panel, said panels being adapted to have the sheet material pass forwardly therebetween from the roll,

30 means for maintaining the second panel in position over the first panel, and a cutter bar secured along a longitudinal edge of the front wall, said second panel being bent along a longitudinal line to form a narrow longitudinal rear part and a wider longitudinal forward part,

35 said narrow rear part projecting widthwise downwardly and forwardly and the wider forward part projecting widthwise forwardly and upwardly and said means comprising frictional engagement of the ends of said narrow rear part with the end walls.
